UNITED STATES PATENT OFFICE.

DAVID L. LINDQUIST, OF YONKERS, NEW YORK, ASSIGNOR TO OTIS ELEVATOR COMPANY, OF JERSEY CITY, NEW JERSEY, A CORPORATION OF NEW JERSEY.

ALTERNATING-CURRENT ELECTROMAGNETIC CONTROLLER.

1,077,355.

Specification of Letters Patent.

Patented Nov. 4, 1913.

Application filed March 3, 1911. Serial No. 612,057.

To all whom it may concern:

Be it known that I, DAVID L. LINDQUIST, a subject of the King of Sweden, residing at Yonkers, in the county of Westchester and 5 State of New York, have invented a new and useful Improvement in Alternating-Current Electromagnetic Controllers, of which the following is a specification.

My invention relates to controlling apparatus especially designed for use in connection with alternating current electric motors.

The primary object of this invention is the provision of means for reducing the volume of current required in starting the 15 motor.

With the usual arrangement of alternating current mechanism comprising a motor and brake as used, for example, in elevator practice, there is a heavy rush of current 20 through the motor at the time it is connected to the mains. The brake magnet at the same time requires a heavy initial current owing to the fact that the magnet circuit of the brake is open until the brake is lifted. 25 The present invention provides means for reducing the starting current applied to the motor until the brake has lifted so as to close its magnetic circuit and reduce the current flow through the brake magnet windings.

30 Other objects of the invention and the exact nature thereof will appear more fully hereafter.

In the accompanying drawings, Figure 1 is a diagrammatic view of an elevator comprising a motor and controlling apparatus 35 designed in accordance with my invention; Fig. 2 is a front elevation view of the mechanism for operating the accelerating switches; Fig. 3 is a sectional end elevation 40 view of the same.

Fig. 1 shows conventionally an elevator system comprising the car C, counterweight W, hoisting cable 11, hoisting drum D, an electric motor M geared in the usual way 45 to the hoisting drum, a brake magnet B, and a switch board 12. Journaled in the switch board 12 is a shaft 13 (Figs. 2 and 3) geared by means of a gear wheel 14 and intermediate gearing not shown to the sprocket 50 wheel and chain gearing 15 (Fig. 1) which is driven by the hoisting drum. Loosely mounted on the shaft 13 is a cam sleeve 16 adapted to be rotated in either direction from its initial position. The coil spring

17 serves to return the sleeve to such 55 position after it has been rotated. An accelerating clutch magnet 18 is adapted, when energized, to connect the cam sleeve 16 for rotation with the shaft 13, in a manner presently to be described. 60 A bail or hook 19 connected to the bottom of the magnet armature 20 surrounds one arm 21 of a bell crank lever 22. The latter is pivoted at 23 to a bracket 24 and has a weighted arm 25 and an arc-shaped segment 26 integral therewith. A lever 27 is pivoted at 28 to a lug formed on the sleeve 16 and carries an arc-shaped rack 29 which is provided with a number of gear teeth 30 at its inner surface adapted to engage but 70 normally out of engagement with the gear teeth of a spur gear 31 fixed to the shaft 13. The spring 32 bears against the lever 27 and forces the rack 29 into contact with the segment 26. Directly over the spur gear 31 75 and a short distance therefrom is an arc-shaped stop-piece 33 which is carried by a bracket 34 secured to the switch board 12. This arc-shaped stop-piece has beveled ends 35 which are adapted to engage correspond- 80 ing beveled ends of the rack 29 when the latter is rotated into engagement therewith.

The switch 4 shown in Fig. 3 is one of four similar accelerating switches 1, 2, 3 and 4, operated by means of the cam sleeve 16 85 and cams thereon. Each switch comprises a spring-pressed swinging contact arm 36 pivoted at 37 to a suitable bracket. The contact arm 36 carries a lug 38 which engages one end 39 of a cam lever 40 which is 90 pivoted at 41. The other end of the cam lever carries a cam roller 42 which bears against the corresponding cam 4^a which is one of a series of graduated cams 1^a, 2^a, 3^a, and 4^a. 95

The operation of the apparatus just described is as follows:—When the magnet 18 is energized its core 20 is lifted and the weighted arm 25 is enabled to swing the bell crank lever 22 about its pivot 23, since the 100 magnet armature no longer bears downwardly on the arm 21 of the bell crank lever. The arc-shaped end 26 therefore moves upwardly carrying with it the rack 29 and causing the gear teeth on the latter to engage the teeth of the gear wheel 31. Since the latter is at this time rotating in one direction or the other a rotary motion is im- 105

parted to the cam sleeve 16 and the cams thereon operate to successively close the corresponding accelerating switches. For example the cam 4^a is rotated out of engagement with the cam roller 42 of the cam lever 40 and allowing the spring 45 to close the switch 4. When the rack 29 has rotated for substantially 90°, it passes out of engagement with the concave surface of the arc-shaped piece 26 on the bell crank lever, and by so doing enables the spring 32 to force the rack 29 out of engagement with the gear wheel 31, and into alignment with the arc shaped piece 26. The latter now 15 acts as a stop to prevent the cam sleeve from being rotated backward by the centering spring 17. Should the spring 32 for any reason fail to disengage the rack from the gear 31, after the cam sleeve has rotated in 20 either direction through substantially 90°, any further rotation of the cam sleeve will cause the beveled edge of the rack 29 to engage one of the corresponding beveled ends 35 of the stop piece 33, and the rack 29 25 will be positively disengaged from the gear and any further rotation absolutely prevented. Upon deenergizing the magnet 18 the armature 20 will drop, carrying with it the lever arm 21 and causing the segment 26 to 30 move out of alignment with the rack 29. This enables the centering spring 17 to rotate the cam 16 and connected cams back to normal position, the cams thereby effecting the opening of the corresponding 35 switches.

Referring now to Fig. 1, the leads *a*, *b* and *c* are connected to the supply mains when the main line switch *S* is closed. If the car switch lever *K* is now moved, to the 40 right for example, a circuit is closed through the magnet coil of the reversing switch *R*, said circuit being from the lead *a* through the reversing switch magnet, car switch *K* and back to the lead *b*. The reversing 45 switch *R* is therefore closed and establishes a circuit for the potential switch magnet *P*. Said circuit may be traced from the lead *b* through the magnet winding, and left hand contacts of the reversing switch *R* to the 50 wire *c*. The potential switch closes and establishes the circuits for the stator of the motor. The lead *b* extends directly to the motor. The leads *a* and *c* are connected through the reversing switch *R* and potential switch *P* to the conductors *a'* and *c'*, respectively, which extend to the motor. The stator windings of the motor therefore receive current and current is also induced in the rotor. The starting resistance *X* is 55 at this time in circuit with the rotor. Said resistance includes in addition to the usual amount of starting resistance an extra resistance *x*, so that the entire resistance *X* is sufficient to reduce the current in both the 60 stator and rotor of the motor to an amount

considerably below that required in starting the motor. When the potential switch is closed as above described current is also supplied to the brake magnet *B*, and to the accelerating clutch magnet 18, the latter being connected between the leads *c'* and *b*. The brake magnet operates as usual to lift the brake and the accelerating clutch magnet lifts its core and closes a switch 18', thereby short-circuiting the extra resistance *x*. The magnet 18, however, is much more sluggish than the brake magnet, that is it has more inertia in proportion to the magnetic pull and this sluggish tendency may be augmented if desired by some well known form of retarding device, such as the dashpot 44, which may be connected to some part of the apparatus, such as the core of the magnet, or the lever 21, as shown or to some other suitable part, so that the switch 18' is not closed until after the brake magnet has operated to lift the brake and close the magnetic circuit of the brake, thereby reducing the current flow through the brake magnet. It will thus be seen that the full starting current is not supplied to the motor until after the brake has lifted and reduced the current required for the brake magnet. In other words, the maximum current required in starting the motor is reduced by retarding the full current flow to the motor until after the brake has operated. The current through the motor when the extra resistance *x* is in circuit is sufficient to prevent the motor from running backward when the brake is lifted and may be for example about one-half of the current required to start the motor. When the extra resistance is short-circuited by the switch 18' the motor receives sufficient current to start. The shaft 13 is therefore caused to rotate and as the clutch lever 27 has been lifted by the accelerating clutch magnet, the cam sleeve is rotated in the manner hereinbefore set forth and effects 100 the successive closing of the accelerating switches 1, 2, 3 and 4, thereby gradually short-circuiting the starting resistance *X* and permitting the motor to be brought up to full speed. When it is desired to stop 105 the motor, the car switch *K* is brought back to central position, thereby effecting the opening of the reversing switch *R* and potential switch *P*, thus cutting off the supply of current to the motor, the brake and the accelerating clutch magnet. The brake is therefore applied to bring the motor quickly to rest. The clutch members 31 and 29 are also disengaged permitting the parts 110 to be restored to initial position. If the car switch is moved to the left, the reversing switch *R'* is operated and the leads *a* and *c* are connected to the conductors *c'* and *a'*, respectively, thereby causing the motor to 115 run in the reverse direction; otherwise the 120 125 130

operation is substantially as already described.

It will be understood that some of the features of electrical control ordinarily employed with this type of motor and elevator apparatus are omitted from the drawings for the sake of simplifying the illustration and because such additional features of control are unnecessary to a full understanding of the present invention.

I do not claim any of the specific features of mechanical construction illustrated in Figs. 2 and 3. This apparatus is specifically shown and described for the purpose of clearly setting forth an operative and practical construction embodying the principles of my invention.

I wish not to be limited to the exact arrangement and details disclosed, and I wish it further understood that the invention may be embodied in various specifically different forms of apparatus within the scope and spirit of my invention.

What I claim as new and desire to secure by Letters Patent of the United States is:—

1. The combination with an electric motor, of an electromagnetic brake, resistance in a circuit of the motor, an electromagnet, means operated thereby for cutting a portion of said resistance out of the motor circuit, means for simultaneously connecting the motor, said electromagnet and brake magnet to a source of alternating current supply, and mechanism controlled by said electromagnet and operated by the motor to cut out the remainder of said resistance.

2. The combination of a motor, an electromagnetic brake, an electroresponsive device slower in operation than the brake magnet and controlled independently of the brake magnet and motor, starting resistance for the motor controlled by said electroresponsive device, and switch mechanism for simultaneously establishing parallel circuits for the motor, the brake and said electroresponsive device.

3. The combination with an electric motor comprising a stator and a rotor, of an electromagnetic brake having its magnet windings connected to the terminals of the stator, resistance in the rotor circuit, an electroresponsive device controlling a portion of said resistance and operable independently of the brake and motor, said electroresponsive device being connected in parallel with said stator windings, and a device for connecting the circuits for the brake magnet, motor, and said electroresponsive device to a source of alternating current supply.

4. The combination with an electric motor, of an electromagnetic brake, sectional resistance in a circuit of the motor, a switch controlling a portion of said resistance, an electroresponsive device for operating said switch, and mechanical means controlled by

said electroresponsive device for effecting the short-circuiting of the remaining portion of said resistance.

5. The combination with an electric motor, of starting resistance for the motor, accelerating switches controlling said resistance, an extra resistance in the motor circuit and of sufficient value to prevent the motor starting, a switch controlling said extra resistance, an electroresponsive device for operating said switch, and means dependent upon the operation of said electroresponsive device to effect the operation of said accelerating switches.

6. The combination of an electric motor comprising a stator and a rotor, sectional starting resistance in circuit with the rotor, accelerating switches controlling said resistance, an extra resistance preventing the motor from starting, a switch controlling said extra resistance, an electromagnet for operating said switch, and mechanism controlled by said electromagnet for effecting the successive operation of said accelerating switches.

7. The combination of an alternating current motor comprising a stator and a rotor, sectional starting resistance in circuit with the rotor, an extra resistance in the rotor circuit, a switch operative to short-circuit said extra resistance, an electromagnet connected to operate said switch and having its electrical circuit connected in parallel with a winding of the stator, and mechanical means operated by the motor and controlled by said electromagnet for effecting the gradual short-circuiting of the starting resistance after said magnet is operated.

8. The combination of an electric motor, a sectional starting resistance for the motor, accelerating switches controlling said resistance, a mechanical device for successively operating said switches, a train of gearing comprising a clutch connecting the said mechanical device to the motor, an extra resistance, a switch controlling said extra resistance, and an electroresponsive device for operating said switch and said clutch.

9. The combination of an alternating current electric motor, an electromagnetic brake, an electroresponsive device, switch mechanism operative to establish the circuits for the motor, the brake magnet and said electroresponsive device, sectional starting resistance for the motor, a series of switches controlling said starting resistance, a mechanical device for operating said switches, means controlled by said electroresponsive device for connecting and disconnecting said mechanical device to and from the motor, an extra resistance, and a switch controlling said extra resistance and operated by said electroresponsive device.

10. The combination of an electric motor, an electroresponsive device, means for simul-

taneously connecting said parts to a source of current supply, and means for preventing the motor from taking a current sufficient to start the motor until said electro-responsive device has operated.

11. The combination of an electric motor, means for connecting the motor to a source of current supply, and automatic means for temporarily preventing the motor from taking sufficient flow of current to start the motor.

12. The combination of an electric motor, a load device connected thereto, means for connecting the motor to a source of current supply, resistance in the motor circuit sufficient to prevent the motor from starting said load device, and automatic means for reducing the resistance in the motor circuit after the motor is connected to receive current.

13. The combination of an electric motor, an electroresponsive device, means for connecting said elements simultaneously to a source of current supply, and means for reducing the maximum value of current supplied to said elements below that required to simultaneously operate said elements.

14. The combination of an alternating current electric motor, an electro-responsive brake having its windings connected in parallel with the stator windings of the motor, means for connecting the motor and brake magnet to a source of alternating current supply, and means for preventing the maximum flow of current through the motor and brake windings exceeding that required to simultaneously operate the brake and start the motor.

15. The combination of an electric motor, a brake, an electro-responsive device, means for supplying current to said parts simultaneously, said electro-responsive device being retarded so as to be slower in action than the brake, and resistance in a circuit of the motor controlled by said electro-responsive device.

In testimony whereof, I have signed my name to this specification in the presence of two subscribing witnesses.

DAVID L. LINDQUIST.
